UNITED STATES PATENT OFFICE

2,416,010

UNIVERSAL JIG

Joseph Bailey Klosz, Clifton, N. J.

Application January 22, 1945, Serial No. 573,950

2 Claims. (Cl. 77—62)

1

This invention relates to a universal jig, and more particularly to such a jig adapted for the drilling of holes in round shafts or the like.

A primary object of this invention is the provision of an improved jig adapted to accommodate a variety of sizes of round rods or shafts for drilling.

A further object of the invention is the provision of such a device having indicating means thereon whereby a length of the shaft may be accurately measured for drilling a hole at a predetermined distance from the extremity thereof.

A still further object is the provision of such a device which may be utilized in conjunction with rods or shafts having either plain or flanged ends.

Still another object is the provision of such a device which will be sturdy and durable in construction, reliable and efficient in operation, and relatively simple and inexpensive to manufacture and assemble.

Other objects will in part be obvious and in part be pointed out as the description of the invention proceeds and shown in the accompanying drawings, wherein there is disclosed a preferred embodiment of this inventive concept.

In the drawings—

Figure 1 is a top plan view of one form of device embodying this invention.

Figure 2 is a side elevational view of the device shown in Figure 1 in association with a flanged rod to be drilled, certain concealed parts thereof being indicated in dotted lines.

Figure 3 is a view similar to Figure 2, but showing certain parts thereof in section in association with a rod having a plain end.

Figure 4 is an exploded perspective view of the device shown in Figures 1 to 3, inclusive, certain removable parts thereof adapted to be utilized with rods having plain ends being shown in exploded position.

Figure 5 is a sectional view substantially along the line 5—5 of Figure 4 as viewed in the direction indicated by the arrows, and

Figure 6 is an end elevational view of the device as shown in Figure 4 in assembled position.

Similar reference characters refer to similar parts throughout the several views of the drawings.

Having reference now to the drawings, the device is comprised of a base 10 consisting of an elongated block member having a pair of aligned parallel ridges 11 triangular in cross-section, extending along the upper surface thereof, between which extends a longitudinally extending

2

groove 12. The side portions of the base 10 are provided with elongated oppositely disposed slots 13, adapted to engage inwardly extending lugs 14 positioned at the extremities of a U-shaped clamp 15 the upper extremity of which is provided with an aperture through which is passed a set screw 16 provided with a winged head 17.

The clamp 15 is adapted to secure to the base 10 a jig member 20 comprised of an elongated block having a V-shaped slot 21 cut in the base thereof, so dimensioned as to overlie the outer angled surfaces of the triangular ridges 11. The member 20 is provided with a bore 22 extending therethrough, and having an interiorly disposed bushing 23 to serve as a drill jig through which a drill may be passed for the purpose of drilling a round rod, in a manner to be hereinafter described, positioned or seated between the ridges 11 and held in position in the V-shaped slot 21 by means of the clamp 15.

The block 20 is provided on its upper surface with a longitudinally extending slot 24 in which is positioned a slide rule 25, the extremity of which is secured to an end plate 26, movable with respect to the block 20. The end plate 26 is mounted on a pair of rods 27 the extremities of which are milled as at 27' adapted to extend into a pair of oppositely disposed parallel aligned bores extending longitudinally into the member 20 and terminating in milled grooves 20', the arrangement being such that the rods 27, end plate 26 and rule 25 are freely slideable with respect to the end of the member 20. A set screw 20" is provided to hold the rods in position. The interiors of the rods 27, which extend through the end plate 26 are provided with bores 28 threaded to receive screws 29 adapted to pass through suitable apertures 30 in an end block 31. The end plate 26 is provided with an inverted V-shaped channel 32 in the lower portion thereof of a configuration substantially identical to that of the channel 21 while the end block 31 is provided with a V-shaped protuberance 33 adapted, when the block is positioned on the end plate 26 to close the V-shaped recess 32.

From the foregoing the operation of the device should now be readily understandable. When it is desired to drill a round rod 35, as best shown in Figure 2, provided with a flange 36, the end block 31 is removed by removal of the screws 29, and the rod seated in the V-shaped depression between the triangular members 11 with the V-shaped groove 21 of the block 20 positioned thereover. The end plate 26 is then seated against the interior of the flange, and moved outwardly

until the rule 25 indicates a desired distance from the extremity of the rod adjacent the bore 22. The wing nut 17 is then tightened clamping the block 20, the rod 35 and the base 10 securely in related assembly, and the drilling operation is carried out through the bore 22, the bushing 23 being adapted to accommodate the desired size of drill.

When a rod 37 having a plain end is adapted to be drilled the end block 31 is positioned on the end plate 26 as best shown in Figure 3, and seated against the outer extremity of the rod 37. The block is then adjusted until the rule 25 indicates the desired distance for drilling, and the above operation repeated.

From the foregoing it will now be seen that there is herein provided a drill jig, adapted to accommodate a variety of sizes and types of rods to be drilled, and so designed as to provide for a plurality of sizes of holes to be drilled in such rods, which accomplishes all the objects of this invention and others including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a jig in combination, a base block having a groove therein, a body block having a groove in its lower face and a transverse bore intersecting said groove adapted to overlie said base block, guide channels in the opposite sides of said base block, a clamp overlying the body block and having terminal ends adjustably mounted in said guide channels adapted to secure said blocks in related assembly with a rod to be drilled extend-

ing therebetween, an end plate slidably associated with said body block, and an indicator secured to said end plate and slidable along said body block.

- 5   2. In a jig in combination, a base block having
a groove therein, a body block having a groove
in its lower face and a transverse bore intersect-
ing said groove adapted to overlie said base block,
guide channels in the opposite sides of said base
10   block, a clamp overlying the body block and having
depending terminal ends adjustably mounted
in said guide channels adapted to secure said
blocks in related assembly with a rod to be drilled
extending therebetween, an end plate slidably
15   associated with said body block, said end plate
having a groove therein of a cross-sectional configura-
tion equivalent to said groove in said body
block, and an end block removably secured to said
end plate for closing said groove in said end plate.

JOSEPH BAILEY KLOSZ.
